UNITED STATES PATENT OFFICE.

GOMER G. BEYNON, OF DES MOINES, IOWA.

CHURN.

SPECIFICATION forming part of Letters Patent No. 717,531, dated January 6, 1903.

Application filed April 9, 1902. Serial No. 101,986. (No model.)

To all whom it may concern:

Be it known that I, GOMER G. BEYNON, a citizen of the United States, residing at Des Moines, county of Polk, and State of Iowa, have 5 invented a certain new and useful Improvement in Churns, of which the following is a specification.

My invention relates to a new and useful improvement in churning, and has for its object to provide a churn which will be very simple in construction and can be manufactured at a comparatively small cost, but will be very efficient and durable in action, and the churn is so constructed that the dasher 15 may be given either a vertical up-and-down movement or a rocking movement.

With these ends in view this invention consists in the details of construction and combination of elements hereinafter set forth and 20 then specifically designated by the claim.

In order that those skilled in the art to which this invention appertains may understand how to make and use the same, the construction and operation will now be described in detail, referring to the accompanying drawings, forming a part of this specification, in which—

Figure 1 is a vertical cross-sectional view of the churn; Fig. 2, a vertical section taken at 30 right angles to Fig. 1; Fig. 3, a plan view of the churn.

A represents the body of the churn. This body tapers upward, and the mouth or open end of the body is cylindrical in form, and 35 upon the inside of the body near the upper end is formed an interiorly-extending flange B, upon which is adapted to rest the cover C. This cover has formed through its center an opening D, through which the shank of the 40 dasher is adapted to extend. Through the cover upon each side of the central opening D are formed the slots E, and in the upper face of the cover at right angles to the slots E and upon each side of the central opening 45 D are formed radial grooves F. The dasher of the churn consists of the shank G, which has extending out from each side of the same the flat blades H, and extending through the shank and out from each side of the same is 50 a pin I. This pin is placed in such a position upon the shank G that when the pin is caused to rest in the grooves F the bottom

blade H of the dasher will be a slight distance above the bottom J of the body, and the grooves F are so arranged in the cover C that 55 when the pin I is caused to rest in the grooves the blades H of the dasher extend across the body of the churn at its narrowest part, and then by oscillating the shank G the lower end of the dasher carrying the blades will be 60 caused to rock within the body A, and the churning may be accomplished in this manner. The bottom J is formed concentric with the pivotal point of the dasher, as shown in Fig. 2. The cover C is provided with notches 65 K, which are adapted to register with projections L, extending inward from the upper rim of the body A. This will cause the cover to always assume a position so that the grooves F will be in the proper position to hold the 70 dasher, so that the bolts H will be at right angles to the greatest width of the body. When it is desired to do the churning by means of the usual vertical reciprocating motion, the shank of the dasher can be turned 75 until the pins I register with the slots E, and then the dasher may be reciprocated up and down in the usual manner, or when it is desired to raise the cover C without disturbing the dasher or raising the same from the 80 churn-body the shank G is turned until the pin I registers with the slots E, and then the cover may be raised to inspect the contents of the churn without disturbing the dasher.

M is a cup secured to the cover C of the 85 churn to prevent any of the contents of the churn from escaping, because of the fact that any milk or other substance working upward through the central opening or slots E will be prevented from spreading any further by 90 the cup M and will flow back through the slots E or central opening D into the churn again.

Of course I do not wish to be limited to the exact construction here shown, as slight modifications could be made without departing 95 from the spirit of my invention.

Having thus fully described my invention, what I claim as new and useful is—

In a churn, a conical tapered body having 100 an interiorly-extending flange and a concave bottom, a cover having a central aperture and a transverse recess in its upper surface formed at right angle to the aperture said cover be-

ing provided with transverse slots and adapted to seat on the flanges of the body, projections extending inward from the upper rim of the body, said projections registering in the 5 transverse slots of the cover, a ring having a flange on its lower end and means for securing the ring to the upper surface of the cover, a dasher-shaft having horizontal rectangular-shaped blades, a pin extending through the

dasher-shaft and adapted to seat in the recess 10 of the cover as and for the purpose described.

In testimony whereof I have hereunto affixed my signature in the presence of two subscribing witnesses.

GOMER G. BEYNON.
